UNITED STATES PATENT OFFICE.

MONROE S. CLAWSON, OF NEW YORK, N. Y.

OXYGEN-GENERATOR.

964,492.

Specification of Letters Patent. Patented July 19, 1910.

Application filed July 29, 1909. Serial No. 510,241.

To all whom it may concern:

Be it known that I, MONROE S. CLAWSON, a citizen of the United States, residing in the city, county, and State of New York, have 5 invented certain new and useful Improvements in Oxygen-Generators, of which the following is a specification.

My invention relates to apparatuses for generating oxygen and has for one of its objects the provision of a device that utilizes the well known chemical affinity of ozone for oxidizable substances by which such substances absorb the oxygen to produce oxids thereof, and then by heating the oxidized 15 material the oxygen is released and may be caught and stored.

Another object of my invention is the provision of an improved form of ozonizer consisting of a glass tube having its outer 20 surface covered with tin foil and connected with one terminal of the secondary of an induction coil or other high potential generator and the other terminal of the induction coil connected with a spiral mounted 25 or supported in a central position in the tube by an insulating plug. By this construction the current is more evenly distributed through the tube, the inter-induction between the spirals assisting in throwing the 30 current to the end of the spiral and making the discharge more diffusible.

Another object of my invention is the provision of an improved device for detecting the changes of temperature in the metal retort containing the oxidizable material consisting in securing a bar of metal to the middle of the retort widely differing from the iron of the retort in the thermo-electric series and connecting said bar to one pole of a galvanometer, while its other pole is connected 40 by wire with one of the pipe connections leading to the retort but remotely therefrom so as not to be influenced by the heat of the retort. By this construction the mean temperature of the retort is indicated at all 45 times.

Still another object of my invention consists in the provision of an ozone and oxygen indicator consisting of a glass bulb circular 50 in one dimension and flat in the other and having holes in the circular portion, one of which is arranged to be secured to the discharge tube of the retort, the other forming the outlet of the bulb, and a hole in one of 55 the flat sides over which is secured a frame

holding a fabric saturated with a chemical that changes its characteristics when in the presence of ozone. Secured over the inlet of the bulb are two spark rods covered with a combustible material that will incandesce in 60 the presence of pure oxygen, said spark rods being connected with the induction coil or other electric energizer.

A further object of my invention consists in the provision of a storage tank for the 65 oxygen that utilizes the principle of the compressing quality of a water column and consists of the oxygen storage tank and a water feed tank on a higher level than the storage tank, the tanks having their lower ends connected by a pipe having a radiating coil intermediate of the tanks. In place of the water feed tank the gas storage tank may be connected with the commercial water supply system. The discharge pipe from the 70 retort ends in a coil in the bottom of the gas storage tank so that the oxygen is cooled by contact with the water in the tank and when steam is used to assist in liberating the oxygen it is condensed. I also provide an auxiliary 75 circulating coil connected with the tank adjacent to its top and bottom and tapped into it at intervals therebetween to keep the temperature of the water in the storage tank reduced, this coil being especially 80 desirable at the end of the discharge from the retort when the percentage of steam is increased.

My invention will be described in detail hereinafter and illustrated in the accompanying drawings in which—

Figure 1 is a diagrammatical view of the apparatus comprising my invention, Fig. 2, a vertical sectional view of the ozone and oxygen indicator, and Fig. 3, an enlarged 95 view of the storage tank.

In the drawings similar reference characters indicate corresponding parts in the several views.

1 indicates the retort employed in my apparatus which is made preferably of iron and contains material such as an oxid of copper, mercury or other substance capable of oxidation, deoxidation and reoxidation repeatedly.

2 indicates an inlet tube tapped into one end of the retort 1 and 3 a discharge tube tapped into the other end of the retort.

4 indicates an ozonizer secured to inlet tube 2 which, as shown in the drawings, is 110

of novel construction but any other ozone generator may be substituted if desired. The ozonizer shown consists of a glass tube or cylinder 5 having a cap 6 on one end, into which tube 2 is tapped, while its other end is plugged as shown at 7.

8 indicates a covering of metal foil applied to the outer surface of glass tube or cylinder 5 and connected with one high potential terminal of induction coil 9 by means of wire 10.

11 indicates a wire spiral secured in plug 7 and extending centrally of the tube or cylinder 5, said spiral being connected by means of wire 12 with the other terminal of the induction coil 9.

13 indicates an air-pump connected by means of tube 14 with ozonizer 4 and tapped into plug 7 as shown.

20 It will be understood that when the induction coil 9 is in operation and air pumped into ozonizer 4 from the pump 13 the electric discharges in the tube 5 transform a percentage of the air into ozone which passing through tube 2 into retort 1 oxidizes its contents.

The storage apparatus consists of the gas storage tank 15 which is normally kept full of water from gravity tank 16 connected with tank 15 by means of tube 17, 18 indicating a radiating coil intermediate of the ends of the tube to keep the temperature of the water reduced. The end of discharge tube 3 empties into tank 15, having a coil 19 on its delivery end.

20 indicates an auxiliary radiating coil connected near the top and bottom of tank 15 and tapped into it at intervals between its ends to cool the contents of the tank, and 40 is especially useful at the end of a discharge, when steam is used to assist the separation of oxygen from the metal oxid and steam in increased quantity accompanies the oxygen.

21 indicates the discharge tube of the 45 storage tank 15 controlled by valve 22.

23 indicates a steam generator or boiler connected by tube 24 with inlet tube 2 having a valve 25 therein.

26 indicates a valve between ozonizer 4 50 and steam generator 23, and 27 a tap between generator 23 and retort 1 that may be used to make a test of the ozone before it reaches the retort or it can be used to relieve the pressure on the retort.

55 The retort 1 is heated in any suitable manner, a burner 28 being shown for the purpose in the drawings but it will be apparent that any other suitable device may be substituted without altering the spirit of my invention.

As stated above the retort 1 is made preferably of iron though any other metal may be substituted without affecting the spirit of my invention.

65 In order that I may be able to know the

temperature of the retort at all times I provide a pyrometer comprising a galvanometer 29 having its positive side connected by wire 30 with a thermopile of which one electrode consists of the retort 1 and the other a bar 31 of any metal having an electrical difference with the retort, as, for example, the retort being of iron the bar 31 could be made of German silver. The end of the bar 31 where secured to retort 1 is preferably made wider as shown at 32 and welded or otherwise secured to the retort opposite its middle so that the galvanometer will at all times register the mean temperature of the retort. The negative side of the galvanometer 29 is connected by wire 32 with pipe or tube 2 at a point remote from the retort 1 so that the heat thereof will not reach it and set up a counter electro-motive force.

Between retort 1 and storage tank 15 I 85 secure an ozone and oxygen indicator consisting of a bulb 33, circular in one dimension and flat in the other as shown in the drawings, and secured to tube 3 by valved connection 34, and having an outlet 35 in its 90 upper side.

36 indicates an opening in one of the flat sides of the bulb and 37 a frame having a piece of fabric 38 mounted thereon and saturated with any chemical that changes color 95 or otherwise shows the presence of ozone, such as starch saturated with an alcoholic solution of tetrathymethyldiamidodiphenylmethane, said frame 37 being held in any suitable manner, so as to cover opening 36. 100

39 indicates spark rods covered with combustible material and connected by means of wires 40 with the two poles of induction coil 9, said spark rods and their coverings being used to indicate when the retort is discharging pure oxygen by the coverings of the rods 39 igniting or becoming incandescent. When this stage is reached the discharge through the bulb 33 is stopped by closing the valve in connection 34 and the oxygen allowed to enter the storage tank. 110

41 indicates a valve between connection 34 and tank 15 that is kept closed until pure oxygen is indicated by the spark rods 39 and is opened when the valve in connection 34 is 115 closed.

In operation the valves 25, 27 and 41 are closed, the induction coil 9 started in operation and air forced through ozonizer 4 by means of air pump 13. The air carrying 120 the ozone passes through pipe 2 into retort 1 where the ozone attaches itself to the material therein, which may as stated be an oxid of copper, mercury or other metal capable of easy oxidation, and oxidizes it, the 125 nitrogen and a small percentage of oxygen passing on through the retort and out through the bulb 33. As soon as the material in retort 1 has absorbed all of the ozone that it is capable of absorbing the ozone 130

passes on through the retort and out through bulb 33 with the nitrogen, its presence with the nitrogen being indicated by the change in the appearance of the fabric 38 which is, 5 as stated, saturated with a chemical that changes color when exposed to ozone. At this time the operation of pump 13 is discontinued, the valves 26 and 34 closed, and the temperature of the retort 1 raised by the 10 heater shown as burner 28. The temperature of the retort is indicated by the scale on galvanometer 29, and as soon as the retort and its contents is heated sufficiently to cause decomposition of the oxid therein so 15 as to liberate the oxygen the valve in connection 34 is opened to permit the escape of the gases liberated by the decomposition of the oxid through bulb 33. At this time the current from induction coil 9 is turned into 20 spark rods 39.

As is well known the gas given off from a retort during the early period of discharge is not always pure oxygen and it is desirable to permit it to escape, but in order that 25 I may know when the gas escaping is pure oxygen I provide the indicator to be used if desired comprising the spark rods 39 covered with a combustible material. During the early period of the discharge the combustible material on rods 39 will glow or be brought to a red heat but as soon as pure oxygen is being discharged the combustible material will ignite or become incandescent. At this time the valve in connection 34 is 30 closed the valve 41 opened and the oxygen permitted to pass into storage tank 15.

As with some substances such as potassium permanganate it is necessary to use steam to assist in liberating the oxygen I 40 provide a steam generator 23 which may be utilized for this purpose if desired, the steam being introduced into retort 1 through pipe 2 by opening valve 25.

As soon as the oxygen has been separated 45 from the oxid the operation above described

may be repeated, the oxidation and deoxidation being carried on indefinitely.

Having thus described my invention what I claim is—

1. An apparatus for generating oxygen 50 comprising a retort containing oxidizable material, an ozone generator communicating with said retort, a storage tank communicating with the retort, and means to raise the temperature of the retort to release the oxygen 55 from the material therein.

2. An apparatus for generating oxygen comprising a retort containing oxidizable material, an ozone generator communicating with said retort, a storage tank communicating with the retort, an ozone indicator located between the retort and storage tank, and means to raise the temperature of the retort to release the oxygen from the material therein. 60 65

3. An apparatus for generating oxygen comprising a retort containing oxidizable material, an ozone generator communicating with said retort, a storage tank communicating with the retort, means to raise the temperature of the retort to release the oxygen 70 from the material therein, and a temperature indicator attached to said retort.

4. An apparatus for generating oxygen comprising a retort containing oxidizable 75 material, an ozone generator communicating with said retort, a storage tank communicating with the retort, an ozone indicator located between the retort and storage tank, means to raise the temperature of the retort 80 to release the oxygen from the material therein, and a temperature indicator attached to said retort.

In testimony whereof I hereto affix my signature in the presence of two witnesses. 85
